UNITED STATES PATENT OFFICE.

FRANK W. HOWARD, OF NEW YORK, N. Y.

UMBRELLA-RUNNER.

1,255,609.

Specification of Letters Patent.

Patented Feb. 5, 1918.

Application filed September 17, 1914. Serial No. 862,162.

To all whom it may concern:

Be it known that I, FRANK W. HOWARD, a citizen of the United States, residing at New York, in the county of New York and 5 State of New York, have invented new and useful Improvements in Umbrella-Runners, of which the following is a specification.

This invention relates to umbrellas and particularly to the runners of umbrellas. A 10 principal object of the invention is to produce a runner which is very simple in construction and which can be very economically manufactured.

A further object of the invention is to 15 produce a runner which can be readily locked to the stick to hold the umbrella open, and at the same time having a form adapting it for attachment to the stretchers.

Further objects of the invention will appear hereinafter.

The invention consists in the general combination of parts and features hereinafter described, all of which contribute to produce an efficient umbrella runner.

25 A preferred embodiment of my invention will be particularly described in the following specification, while the broad scope of my invention will be pointed out in the appended claims.

30 In the drawings:

Figure 1 is a side elevation of the runner and its contiguous parts, the umbrella stick being broken away.

Fig. 2 is a vertical section through the 35 runner.

Fig. 3 is a detail showing a form of locking member which is illustrated in Figs. 1 and 2.

Fig. 4 is a cross section taken about on the 40 line 4—4 of Fig. 1.

Fig. 5 is a side elevation showing another form of locking member for the runner.

Fig. 6 is a vertical section through this runner.

45 Fig. 7 is a cross section taken on the line 7—7 of Fig. 5.

Fig. 8 is a side elevation of another form of runner.

Fig. 9 is a vertical section through the 50 runner shown in Fig. 8.

Fig. 10 is a cross section on the line 10—10 of Fig. 8.

Fig. 11 is a side elevation of the locking member detached.

Fig. 12 is a side elevation showing another 55 form of runner.

Fig. 13 is a vertical section through a runner of this form.

Fig. 14 is a cross section on the line 14—14 of Fig. 12.

Fig. 15 is a side elevation showing another 60 embodiment of my invention.

Fig. 16 is a vertical section showing the runner illustrated in Fig. 15.

Referring more particularly to the parts, 65 the runner 15 preferably comprises a sleeve 16 having a substantially cylindrical body 17 at the upper end of which any suitable means may be provided for securing the runner 15 to the stretchers 19 of the umbrella. But for this purpose I prefer to employ a conical collar 18 rigid with the sleeve and having eyes 18^a to which the ends of the stretchers 19 attach. The sleeve 16 encircles the runner stick 20 and against the 70 side of this stick there lies unattached and loosely, so as to be also encircled by the sleeve, a locking member 21. This locking member may have any suitable form which will facilitate its operating normally to permit the free movement of the runner along the stick, but which is movable into a position in which it will jam between the sleeve 16 and the stick and lock or clamp the runner to the stick.

85 This locking member 21 is preferably in the form of a stem extending longitudinally of the runner and arranged to rotate on a longitudinal axis. In order to rotate the locking member, it is preferably formed 90 with an integral extension 22 which, if desired, may be in the form of a loop formed near the middle point of the stem and projecting through an opening or slot 23 in the side of the sleeve which permits a rotary 95 movement of the locking member. The stem of this locking member has a greater transverse dimension in one transverse or radial plane than in another, and this form may be produced by forming the stem with slight 100 bows 24 and 25. These bows 24 and 25 may bend in opposite directions, which insures a good gripping or clamping effect with either direction of movement of the extension or finger piece 22 from its neutral or mid-105 position.

It will be seen that the locking member and the sleeve are arranged so that the

sleeve holds the locking member in position and retains it against the stick. This function is preferably performed by the extension 22 and bolt 23 as in the embodiment 5 shown in Fig. 1, and to a certain extent by the bent ends of the bows 24 and 25 which project beyond the ends of the sleeve.

In the embodiment of the invention shown in Figs. 5 to 7, the locking member 26 is 10 of simpler form and is preferably formed so that its stem 27 is in the form of a bow, the upper end of the bow being formed with an extension or hook 28 which projects over the upper end of the sleeve 29 where it 15 joins the collar 30. The lower end of the locking member has an outwardly disposed extension 31 which is located at the lower edge of the sleeve and performs the double function of assisting in retaining the locking member in the sleeve and enabling the body of the same to be rotated to lock or unlock the sleeve on the stick. The locking members of the forms described above are 20 preferably formed of resilient wire.

25 Instead of producing the locking effect in the locking member by forming it with a bend, I may simply form a flattened extension 32 on the locking member, as illustrated in the embodiment of the invention 30 shown in Figs. 8 to 11. In this embodiment, the stick 33 is of the same form as that described, and if desired, the runner may also be of the form illustrated in Fig. 5, but, if desired, I may form the sleeve 34 of the runner with a socket 35 and this socket preferably extends longitudinally of the sleeve so as to present a recess in which the locking member 36 may lie. I do not limit myself 35 however to the locking member extending longitudinally of the sleeve, as it is obvious that a simple socket can be formed on the inner face of the sleeve receiving a locking member which will jam between the stick and the sleeve in one position, and leave 40 the runner free in another position. However, a socket extending throughout the entire length of the sleeve is most convenient and economically manufactured and when the runner is of this form, it enables the 45 sleeve to fit very neatly to the stick, whereas, in the embodiment of the invention shown in Figs. 4 and 7, the sleeve is preferably of considerably larger diameter than the stick.

50 Referring to the embodiment shown in Figs. 12 to 14, in this form of the invention I prefer to employ a sleeve 37 having a socket 38 formed therein and preferably also provided with an opening or slot 39. The locking member extends out through the slot 60 to form a finger piece 40 and this finger piece is preferably formed of wire with integral extensions 41 which have any suitable form adapted to jam when the finger piece is rotated. Obviously the extension 41 can if 65 desired be formed only on one end of the

wire, and I do not confine myself to this flattened form of extension, in fact, an eccentric knob or any other simple means may be employed which would jam the sleeve on the stick when the locking member is rotated to the proper position.

70 With the embodiment of the invention shown in Figs. 5 and 8, it is evident that if the runner is removed from the stick, the locking member can be readily removed from 75 the sleeve. In the form shown in Fig. 8, the socket is open on the side toward the stick which permits this easy disengagement of the locking member.

75 In the embodiment illustrated in Figs. 15 and 16, I provide means to prevent the locking member from scarring the stick, and this means also adapts the runner for clamping readily on a steel stick. For this purpose, I prefer to provide a keeper 42 in the 80 form of a light plate the ends of which are bent outwardly to form bearings for the ends of the bent locking key 43, and are crimped over the ends of the sleeve to prevent dislodgment of the keeper. When the 85 locking key 43 is rotated to lock the runner, its offset or bent side pushes against the body of the carrier 42 and forces the same over firmly against the stick so as to clamp the 90 stick friction tight. This plate also prevents the key from dropping out and keeps the key from sliding around in the sleeve because it will be stopped by the stretchers.

95 It is understood that the embodiment of the invention described above is only one 100 of the many forms or embodiments my invention may take, and I do not wish to be limited in the practice of my invention nor in my claims to the particular embodiment set forth.

105 What I claim is;—

110 1. In an umbrella, in combination, a stick, a locking member lying loosely against the side of the stick and unattached to the stick, a runner having a circumferential wall encircling the stick and the locking member and retaining the locking member in the space between the side of the stick and the circumferential wall of the runner, said locking member being movable relatively to the stick on an axis extending substantially parallel with the stick and runner and having a form adapted to jam the runner on the stick in one position of the locking member, and permit the free movement of the runner in another position of said locking member.

115 2. In an umbrella in combination, a stick, a locking member lying loosely against the side of the stick and unattached to the stick, a runner having a circumferential wall encircling the stick and the locking member and retaining the locking member in the space between the side of the stick and the circumferential wall of the runner, said locking member being rotatable on a longitudi- 120

125 130

nal axis and having a form adapted to jam the runner on the stick in one position of the locking member, and permit the free movement of the runner in another position of said locking member.

3. In an umbrella, in combination, a stick, a locking member lying loosely against the side of the stick and unattached to the stick, a runner having a circumferential wall enclosing the stick and the locking member and retaining the locking member in the space between the side of the stick and the circumferential wall of the runner, said locking member being rotatable on a longitudinal axis and having different dimensions in different radial planes from its axis of rotation whereby it will jam the runner on the stick in one position of the locking member, and permit the free movement along the runner in another position of said locking member.

4. In an umbrella, in combination, a stick, a locking member lying loosely against the side of the stick and unattached to the stick, a runner encircling the stick and locking member and retaining the locking member adjacent the stick, said locking member consisting of a resilient stem rotatable on a longitudinal axis and adapted to jam the runner on the stick in one position of the locking member, and permit the free movement of the runner in another position of said locking member.

5. In an umbrella, in combination, a stick, a runner encircling the stick, a locking member held between the stick and the runner having a stem extending longitudinally of the runner, said locking member having an integral extension for rotating the same on a longitudinal axis, said stem being arranged to jam against the stick when said extension is swung toward the locking position, and normally permitting the free movement of the runner on the stick.

6. In an umbrella, in combination, a stick, a runner encircling the stick, a locking member held between the stick and the runner having a stem extending longitudinally of the runner, said locking member having an integral extension for rotating the same on a longitudinal axis, said stem being arranged to jam against the stick when said extension is swung toward the locking position,

and normally permitting the free movement of the runner on the stick, said extension projecting beyond the wall of said runner, said runner and said locking member being arranged to engage to retain the locking member on the runner.

7. In an umbrella, in combination, a stick, a runner encircling the stick, a locking member held between the stick and the runner having a stem extending longitudinally of the runner, said locking member having an integral extension for rotating the same on a longitudinal axis, said stem being arranged to jam against the stick when said extension is swung toward the locking position, and normally permitting the free movement of the runner on the stick, said runner having an opening in the wall thereof, and said extension being arranged projecting through said opening.

8. In an umbrella, in combination, a stick, a runner consisting of a sleeve adapted to slide on said stick, said sleeve having a socket, a locking member rotatably mounted in said socket for engaging the stick when said member is rotated to lock the runner thereto, said runner and said locking member interlocking so that said runner retains said locking member, said socket being open on the side toward said stick and permitting the removal of said locking member from said runner, when said runner is removed from said stick.

9. In an umbrella, in combination, a stick, a runner encircling the stick and consisting of a sleeve with an elongated socket extending longitudinally of and formed in the face of said sleeve adjacent the stick, a locking member having a stem disposed longitudinally in said socket and rotatable therein about an axis extending longitudinally with said stick, said stem having different dimensions in different radial directions from said axis whereby the rotation of said stem may lock said runner to said stick.

In testimony whereof I have hereunto set my hand in presence of two subscribing witnesses.
